(57) **CLAIM**

The ornamental design for a footwear outsole, as shown and described.

DESCRIPTION

FIG. 1 is a medial side perspective view of a footwear outsole showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines showing a footwear upper and periphery in FIGS. 1–6 represent the portions of the design that form no part of the claim. The broken line forming an oval shape in FIGS. 1 & 7 defines the boundary of the design. The broken line and the area within, form no part of the claim.
